UNITED STATES PATENT OFFICE.

JAMES F. SPECK, OF HEWITT, OKLAHOMA.

NUT-LOCK.

978,499.

Specification of Letters Patent. Patented Dec. 13, 1910.

Application filed May 21, 1910. Serial No. 562,697.

To all whom it may concern:

Be it known that I, JAMES F. SPECK, citizen of the United States, residing at Hewitt, in the county of Carter and State of Oklahoma, have invented certain new and useful Improvements in Nut-Locks, of which the following is a specification.

This invention comprehends certain new and useful improvements in nut locks, and 10 the invention has for its object a quite efficient device of this character which is designed particularly for use in connection with rail joints, and which includes a chair adapted to receive and support the meeting 15 ends of the rail sections, and a single member connected to the chair to engage with and positively lock all of the nuts at the joint, the said member being movable relatively to the chair in order to release all the 20 nuts simultaneously, when occasion requires.

A further object of the invention is a device of this character which serves to materially increase the strength and rigidity of the joint, and which obviates the necessity 25 of employing track walkers to inspect the joints and tighten the nuts.

With these and other objects in view, as will more fully appear as the description proceeds, the invention consists essentially 30 in certain constructions, arrangements, and combinations of the parts that I shall hereinafter fully describe and claim.

For a full understanding of the invention, reference is to be had to the following description and accompanying drawings in which:—

Figure 1 is a sectional perspective view showing a rail joint equipped with my improved nut lock; Fig. 2 is a transverse section thereof; Fig. 3 is a detail perspective view of the rail chair, showing the locking means carried thereby, the pivoted plate being removed.

Corresponding and like parts are referred 45 to in the following description and indicated in all the views of the drawing by the same reference characters.

The present invention is designed particularly for use in connection with rail joints, 50 and, for the purpose of illustration, is shown and described as applied to the meeting ends of the companion rail sections 1 which may be of the usual or any desired construction or design.

55 A fish plate 2 lies against one side of the

meeting ends of the rail sections and conforms to the contour thereof so as to fit snugly thereagainst, the upper end of the fish plate fitting beneath the overhanging tread portions of the rail sections, and the lower end portion of the fish plate extending entirely over the adjacent base flanges. At 60 its lower end the fish plate is integral with a substantially flat base plate 3 that extends transversely beneath the meeting ends of 65 the rail sections and forms a support therefor, a relatively short lip 4 upstanding substantially perpendicularly from the base plate 2 and engaging the corresponding base flanges to hold the rail sections against lateral movement relative to the base plate and thus maintain the rail sections in alinement at all times. The base plate, fish plate, and lip co-act to constitute a chair for the reception of the meeting ends of the rail sections. 70 The fish plate 2 is formed in proximity to its opposite ends with pairs of longitudinally spaced openings 5 which register with the usual openings that extend transversely through the web portions of the meeting 75 ends of the rail sections. A plurality of bolts 6 are passed respectively through these registering openings to connect the meeting ends of the rail sections together, the bolts being engaged by nuts 7 that are all arranged in abutting relation to, and are 80 screwed up tight against the fish plate. 85

The specific locking means consists essentially of a single keeper bar 8 which is substantially straight throughout its length and has substantially parallel side edges, the keeper bar being supported from the fish plate above the nuts 7 and being disposed longitudinally, that is, in the direction of the length of the rail. The ends of the keeper bar are 90 bent substantially perpendicularly as indicated at 9, and bear respectively against the opposing faces of ears 10 that project substantially perpendicularly outwardly and laterally from the upper end of the fish plate, 95 the ears being preferably located at the side or vertical edges of the fish plate, as shown. The ears and bent ends 9 are correspondingly perforated, and a pivot pin 11 is passed through each adjacent ear and bent 100 end 9 so as to pivotally connect the locking bar to the fish plate to turn about a longitudinal horizontal axis. The plurality of locking tongues 12 are extended angularly 105 from one of the side edges of the keeper bar, 110

at suitable longitudinally spaced points. Each locking tongue lies substantially in the plane of the keeper bar and is disposed substantially perpendicularly to the length thereof.

In its normal or operative position the keeper bar is disposed on the opposite side of its pivotal axis from the fish plate 2, and lies in a substantially vertical plane 10 with its lower edge bearing upon the upper peripheral faces of all of the nuts 7, which are turned square for this purpose. The tongues depend from the keeper bar and fit snugly between the nuts of the respective 15 pairs whereby to positively hold the nuts against turning movement. In addition to this function, the locking tongues serve to weight the keeper bar to hold the same in an operative position against accidental 20 swinging movement away from the nuts.

When it is desired to simultaneously release all of the nuts, it is merely necessary to lift the keeper bar to swing the same away from the nuts so that the locking 25 tongues are withdrawn from between the same. It will therefore be apparent that the release of the nuts may be expeditiously effected, and does not involve any injury to the parts of the nut lock as would hinder 30 or prevent its reuse.

It is to be understood that the invention is not limited to use in connection with rail

joints, but is susceptible of general application.

If desired, the chair may also include a 35 fish plate 13 which is pivotally connected to the lip 4 to turn about a longitudinal axis, the fish plate being adapted to be swung against adjacent sides of the rail sections and being formed with openings 40 through which the bolts 6 are passed. By employing this second fish plate, a more complete chair is provided.

Having thus described the invention, what 45 I claim is:

The combination with a rail chair including a base plate, and a fish plate upstanding from one side thereof, the fish plate being formed with pairs of longitudinally spaced bolt openings; of a keeper bar disposed 50 longitudinally above the bolt openings and pivotally connected to the fish plate to turn about a longitudinal axis, and longitudinally spaced locking tongues extended angularly from one longitudinal edge of the keeper 55 bar and normally depending therefrom between the bolt openings of each pair.

In testimony whereof, I affix my signature in presence of two witnesses.

JAMES F. SPECK. [L.S.]
